UNITED STATES PATENT OFFICE

ROBERT G. FLEMING, OF CHICO, CALIFORNIA, ASSIGNOR, BY MESNE ASSIGNMENTS, TO SMOKADOR MANUFACTURING COMPANY, INC., OF NEW YORK, N. Y., A CORPORATION OF DELAWARE

ASH TRAY

Application filed December 5, 1924, Serial No. 754,088. Renewed July 17, 1928.

This invention relates to certain new and useful improvements in ash trays and has for its object the provision of a tray of simple and economical construction and attractive appearance, which may be easily and quickly attached to and removed from a desk, table or other support.

A further object of the invention is to provide novel means for attaching the tray and more specifically means wherein the support for the tray proper is rotatable so as to adjustably effect securing of the tray to the support.

Another object of the invention is to provide a novel smoker's stand unit adapted to be suitably supported and having an ash tray at the upper end of an elongated tube of relatively small diameter, and having a detachably connected receptacle for the waste at the lower end of the tube, preferably of transparent material, so that when a large amount of waste has accumulated the receptacle may be disconnected from the lower end of the tube and the waste removed.

A still further object of the invention is to provide a desk ash tray wherein ashes, stubs and matches placed therein are caused to gravitate into a receiver which is air-sealed, thereby to not only trap matter dumped into the tray but also to prevent the escape of odors emitted by the contents of the receiver.

The invention has still further and other objects which will be later herein set forth and of themselves manifested in the course of the following description:

In the drawings:—

Fig. 1 is a view partly in side elevation and in longitudinal section illustrating an embodiment of the invention;

Fig. 2 is a section on line 2—2 of Fig. 1.

Fig. 3 is a section on line 3—3 of Fig. 1.

Fig. 4 is a section on line 4—4 of Fig. 1.

Fig. 5 is a longitudinal sectional view of modification;

Fig. 6 is a top plan view, the tray being removed;

Fig. 7 is a top section on line 7—7 of Fig. 5 and

Fig. 8 is a top section on line 8—8 of Fig. 5.

In proceeding in accordance with the pres-

ent invention as illustrated in Fig. 1, a tubular stem 1 is provided which is open at its opposite ends and which is exteriorly threaded and has its upper end 2 flared and rigidly secured to the open bottom of an ash tray 3. The tray 3 has cigar or cigarette rests 4 secured to its top and has a depending hollow neck 5 which is rotatably received in the upper end of a frame 6. The frame 6 is formed with a tubular post 7 and is longitudinally slotted at 8 and has a handle 9 on its outer side. The upper end of post 7 has a clamping jaw 10 fixed thereon and preferably integral therewith and faced with felt or other material to prevent marring of the finish of the desk or table top.

A movable jaw 12 is threaded onto stem 1, the threaded portion of which latter is in the post, and said jaw 12 has a constricted portion, or web 13 that extends through and projects from the frame 6, being held from turning by the walls of the slot 8. A cover 14 is threaded onto the lower end of stem 1 and is rigidly secured thereto by pins 15, the cover having an inturned flange 16 notched at 17 to receive ears 18 formed on the mouth of a preferably glass receiver 19. A gasket 20 is engaged by and between the cover and the ears 18 so as to air-seal the mouth of the receiver. A holder 21 for packages of matches may be secured to an ear 22 formed on the handle.

In the modified form of the invention, the receiver is eliminated and accordingly the tray 30 has a closed bottom and is removably engaged with a preferably open head 31 having a depending perforated neck 32. A threaded stem 33 has its upper end reduced and extending into the perforation of neck 32 and is rigidly secured thereto by a pin 33'. The neck 32 is rotatable in the upper end of a frame 34, which latter has a rigid jaw 35, a handle 36 and a longitudinally slotted post 37. The lower end of the stem 33 has a guide 38 secured thereto by riveting the lower end of stem 33 thereto as shown at 39. A jaw 40 is threaded onto the stem 33 and has a reduced neck 41 operating in the slot 42 of post 37.

In both forms of the invention, the op-

posed cooperative, clamping jaws engage opposite faces of the top or top structure of a desk or table, the movable jaw being operated by gripping and turning the tray 3 in Fig. 1, or the head 31 in Fig. 5, thus effecting movement of the lower jaw longitudinally of the frame so as to cause the jaws to grip or be released from gripping engagement with the top.

10 As the ash tray is outside the frame, it is in convenient position to be grasped and turned at will. And as the tray is connected to the stem, and the latter to the movable jaw 12, clamping and unclamping are readily effected by merely manipulating the ash tray.

15 From the above it will be apparent that the invention affords a rigid support for the tray and wherein same is connected to and disconnected from the furniture top or other support from above the latter, thus enabling the operation to be easily and quickly performed. It will also be apparent that the movable jaw in each instance is actuated by the stem 1 or 33 which latter constitutes a carrier for the tray proper.

20 In the form of the invention illustrated in Fig. 1 stubs, ashes, and burned or lighted matches deposited in the tray will gravitate through the open bottom of the latter and through stem 1 and enter the receiver 19 where same will be trapped. Owing to the carbon dioxide gas resultant from the products of combustion of burning stubs or matches entering the receiver, being heavier than air, the same will remain in the receiver, thereby trapping all odors and preventing their escape into the room. The receiver may be easily and quickly removed at will to dump its contents, by mere turning movement of the receiver to bring its ears 18 into register with notches 17. In both forms illustrated, the stem is held against longitudinal movement in the frame 6, at the upper end by the tray and at the lower end by the 25 cover 14 (Fig. 1) or the guide 38 (Fig. 5).

40 What is claimed is:—

1. In an ash tray, a frame having a rigid jaw, a movable jaw, means to hold the movable jaw against turning, a stem threaded into 45 engagement with the movable jaw to move same toward and from the rigid jaw, and an ash tray proper carried by the upper part of the stem.

2. In an ash tray, a frame having a rigid 50 jaw, a movable jaw, means to hold the movable jaw against turning, a stem, means for operating the movable jaw by the stem to move same toward and from the rigid jaw, and an ash tray proper carried by the upper 55 part of the stem.

3. In a device of the character described, in 60 combination, a frame and a jaw carried thereby, a threaded stem rotatable relative to said frame, an ash tray connected to said stem to rotate the latter by rotation of said tray, a

second jaw movable relatively to the first mentioned jaw, and connections whereby rotation of said stem by said tray is adapted to cause approaching and receding movements between said jaws.

4. In a device of the character described, in combination, a frame and a jaw carried thereby, a threaded stem rotatable relative to said frame, an ash tray connected to said stem to rotate the latter by rotation of said tray, 70 a second jaw movable relatively to the first mentioned jaw and connections whereby rotation of said stem by said tray is adapted to cause approaching and receding movements between said jaws, said frame having a guiding slot, one of said jaws having a portion passing through said slot and having threaded engagement with said stem.

5. In a device of the character described, in combination, a frame and a jaw carried thereby, a threaded stem rotatable relative to said frame, an ash tray connected to said stem to rotate the latter by rotation of said tray, 75 a second jaw movable relatively to the first mentioned jaw, and connections whereby rotation of said stem by said tray is adapted to cause approaching and receding movements between said jaws, said frame having a guiding slot, the said second jaw having a portion passing through said slot and having threaded engagement with said stem, the other of said jaws being fixed to said frame.

6. In a device of the character described, in combination, and a frame and a jaw carried thereby a hollow threaded stem open at opposite ends rotatable in said frame, an ash tray connected to the upper end of said stem to rotate the latter by rotation of said tray, said tray communicating with said upper end of said stem, a second jaw threaded on said stem for movement toward the other jaw, means adapted to hold said movable jaw against turning as said stem is rotated, and an ash receiver carried by the lower end of said stem.

7. In a device of the character described, in combination, a frame including a fixed clamping jaw, a handle, and a tubular post, a rotatable ash tray, a stem rotatable in said post and connected to be rotated by rotation of said tray, and a clamping jaw threaded on said stem and held from rotative movement relative to said post.

8. In a device of the character described, in combination, a frame including a fixed clamping jaw, a handle, and a tubular post, a rotatable ash tray, a tubular stem one end of which is in communication with said tray and rotatable in said post and connected to be rotated by rotation of said tray, a receiver in communication with the other end of said stem, and a clamping jaw threaded on said stem and held from rotative movement relative to said post.

9. In a device of the character described, a

tubular frame, an externally threaded tubular stem rotatable in said frame, a pair of clamping jaws, one of the same being longitudinally movable relatively to said tubular frame and having a threaded connection with the threaded portion of said stem whereby the rotation of the latter will move said jaw toward and from the other jaw, and an ash tray mounted on and above said parts and having an opening communicating with the interior of said tubular stem.

In testimony wherof I affix my signature.

ROBERT G. FLEMING.
